CARPET UNDERLAY

Carl R. Toothaker, Barrington, R.I., assignor to United States Rubber Company, New York, N.Y.

Filed Nov. 12, 1963, Ser. No. 77,357

Term of patent 14 years

(Cl. D92—4)

FIG. 1 is a plan view of a carpet underlay embodying my new design;

FIG. 2 is a sectional view taken along the plane indicated by line 2—2 in FIG. 1;

FIG. 3 is a sectional view taken along the plane indicated by line 3—3 in FIG. 1; and

FIG. 4 is a perspective view of one surface of the carpet underlay.

The characteristic features of the carpet underlay design reside in a herringbone pattern formed by spaced zigzag ribs, said ribs having raised portions located at the apices thereof.

I claim:

The ornamental design for a carpet underlay, substantially as shown and described.
